INFLATABLE PACKER WELL TOOL
 Billy C. Malone, Houston, Tex., assignor to
 Lynes, Inc., a corporation of Texas
 Filed Aug. 9, 1961, Ser. No. 130,305
 11 Claims. (Cl. 166—187)

The present invention relates to a well tool, and more particularly to a well tool and a valve arrangement therefor.

The present invention relates to an improvement of the invention disclosed in my application bearing Patent No. 3,085,628 which issued on April 16, 1963 for "Inflatable Well Tool."

The present invention relates to an inflatable well tool, and more particularly to an inflatable well tool which incorporates features whereby the well tool may be set in a well without necessarily manipulating the support string on which the inflatable element is lowered into the well.

An object of the present invention is to provide a well tool which may be quickly and easily lowered into a well bore and expanded to set in the well bore.

Yet a further object of the present invention is to provide a well tool incorporating an expandable element thereon and valve means which is operable after the expanded means have been expanded to lock the expanding fluid within the expanding means.

Yet a further object of the present invention is to provide a valve arrangement for a well tool wherein an expandable means is to be expanded and set in a well bore wherein the valve is constructed and arranged so that it is locked in open position until a predetermined amount of pressure is exerted to set the expanding means in the well bore whereupon the valve means is actuated to close and lock the expanding fluid within the expanding means.

Still another object of the present invention is to provide in a well tool with an expandable means, a means of closing off the expandable means to further inflating fluid upon a predetermined fluid pressure differential between the fluid pressure in the well bore and the fluid pressure in the expandable means.

Yet a further object of the present invention is to provide in a well tool with an expandable means a means of locking the expanding fluid within the expandable means upon a predetermined pressure differential existing between the fluid pressure in the well and fluid pressure in the expandable means.

Other objects and advantages of the present invention will become more readily apparent from a consideration of the following description and drawings wherein:

FIG. 1 is a vertical section of a well bore illustrating a well tool with expandable means thereon which is expanded or set in the well bore;

FIG. 2 is an enlarged partial vertical sectional view illustrating the structural details of the upper head when the valve means is in open position;

FIG. 3 is a sectional view on the line 3—3 of FIG. 2 to more clearly illustrate the structural relationship of the components of the present invention;

FIG. 4 is a sectional view on the line 4—4 of FIG. 2 and illustrates a form of the means utilized to control the functioning of the valve means;

FIG. 5 is an enlarged partial sectional view showing the relation of the valve means to other components after the valve means has been actuated to seal off the expandable means;

FIG. 6 is a sectional view showing the inner part of the tool elevated relative to the packer; and

FIG. 7 is a continuation of FIG. 6 and shows the position of the tool components when the packer is deflated.

In FIG. 1, the well bore is generally indicated by the numeral 6. In some instances, the well bore 6 will be provided with lining such as pipe or the like and in other instances it may be an open hole which has no lining. The present invention may be used in either situation.

The present invention is designated generally by the numeral 7 and is supported within the well bore 6 on any suitable means such as the support member 8, which is illustrated in FIG. 1 as being well pipe. The supporting member 8 extends to the earth's surface and provides a means whereby the invention 7 may be initially lowered into the well bore 6 and positioned therein and thereafter removed from the well bore. Also, if the member 8 is pipe, such pipe forms a means for conducting well fluids from the formation 15 up through the tool illustrated generally at 9 and to the earth's surface.

An expandable means or element designated generally at 22 is provided on the tool 9 and is illustrated in FIG. 1 of the drawings in expanded or set position. The tool 9 including expandable means 22 is supported on a tubular member 10, and the tubular member 10 is in turn adapted to be connected to the support means 8 shown as pipe in FIG. 1. The tubular member 10 illustrated in FIG. 1 of the drawings extends through the packer tool 9 as shown in FIG. 2 and includes the extension 11 which depends below the packer tool 9 on which extension the perforated plug 12 is mounted.

It will be noted that after the well tool 9 has been set in the well bore 6, the formation 15 may communicate through the plug 12 and depending portion 11 of the tubular member 10 whereby the well fluids from the formation 15 are conducted through the expandable means 22 set in the well bore 6 and through tubular member 10 up to the well bore.

Circumferentially spaced and longitudinally extending grooves 16 are provided in the depending portion 11 of the tubular member 10 and form leak passage means whereby the expandable means 22 of tool 9 may be released from expanded position in the well bore 6 when desired, as will be described in greater detail hereinafter.

The well tool 9 includes spaced annular heads designated generally by the numerals 20 and 21 in FIG. 1 of the drawings. The expandable means designated generally by the numeral 22 extends between and is connected to the heads 20 and 21 as shown in the drawings.

The upper head 20 includes the annular portions 25, 26, and 29 which are connected together as shown in FIG. 2 by suitable means such as threads 27 and 30, respectively. Suitable seal means 28 are provided between the members 25 and 26 to inhibit the leakage of fluid therebetween.

The tubular member 10 is connected to the portion 26 of the upper head 20 by the engaging threaded area designated generally at 32 in FIG. 2 of the drawings. The tubular member 10 may be formed of several longitudinal sections that extend through the packer tool 9, such sections being connected together by any suitable means such as by the threads 33 as shown in FIG. 2. Suitable seals as shown at 34 may be provided between the longitudinal sections forming the tubular member 10 to inhibit the leakage of fluid from between the threaded sections. Additionally, suitable seal means are provided at 35 between the portion 26 of the head 20 and the tubular member 10 to further inhibit leakage of fluid therebetween and a suitable seal 37 is provided between the portion 26 and tubular member 10 to prevent well fluid which is conducted into the tool through port means 70 from passing between the member 10 and annular head portion 26.

It is to be noted that the longitudinally extending por-

ion of the tubular member 10, such as represented by the numeral 40, which extends through the packer element 9 is of suitable size relative to the upper packer head 20 so that an annular, longitudinally extending chamber 41 is formed therebetween. Disposed within the chamber 41 is the annular sleeve means designated generally by the numeral 42, which sleeve valve surrounds the tubular member 10 as shown in the drawing and controls fluid communication to the expandable means 22 on the well tool 9.

The annular sleeve valve 42 is provided with suitable seal means 43, 44, and 45 longitudinally spaced on the valve means 42 to seal between the tubular member 10 and the valve means 42 as will be described in greater detail hereinafter. Similarly, suitable spaced seal means 46 and 47 are provided between the portion 26 of the upper packer head 20 and the sleeve valve 42 to seal herebetween.

The expandable means 22 as illustrated in FIG. 2 of the drawings includes suitable cover means represented by 50 for engaging and sealing against the wall of the well bore 6 and suitable reinforcing represented by the numeral 51 is provided for reinforcing the expandable means 22. An inner covering or inner tube 52 is shown as being provided which surrounds the tubular member 10 and extends longitudinally of reinforcing 51 and outer cover means 50, the end of the inner tube 52 being received within the wedge member 53 as shown in FIG. 2. The wedge member 53 engages the upper end of the reinforcing 51 in the packer head 20 to aid in initially securing and retaining the components of the expandable means 22 engaged with the packer heads during expansion and contraction thereof.

The construction in lower packer head 21 is similar in that wedge members 53 are provided for aiding in holding the reinforcing in the lower head and for receiving the end of the tube 52. Cover means 50 may be bonded to each of the heads 20 and 21 in any suitable well-known manner.

It can be appreciated that any suitable form of expandable means 22 may be employed with the present invention without departing from the scope of the invention as disclosed and claimed herein.

Suitable port or passage means as represented generally at 60 are provided in the tubular member 10 whereby expanding or inflating fluid may be conducted from the tubular member to the expandable means 22. To this end, a port 64 is provided in the sleeve valve 42, and as shown in FIG. 2 of the drawings, is initially aligned with the port means 60 in the tubular member 10. It will be noted that the chamber 41 formed between the tubular member 10 and the head portion 26 includes an enlarged annular portion 65 formed in the wall of head 26 extending longitudinally thereof whereby fluid conducted from the port means 60 and 64 will flow through the enlarged portion 65 to be discharged into the port means 66 of sleeve valve 42 below the seal means 45. The fluid will then flow through the annular space 67 formed between the valve means 42 and tubular member 10 to be discharged into the expandable means 22 to effect inflation thereof.

The port means 70 in upper packer head 20 extends through the portion 26 of the packer head 20 and communicates with the chamber 41 in the packer head 20 whereby fluid pressure in the well bore 6 may pass therethrough and act on the end 42' of the sleeve valve 42.

The sleeve valve 42 is seated on snap ring 71, and the snap ring 71 fits in the groove 72 in the portion 25 of the packer head 20. Suitable means as illustrated generally at 75 are provided for locking or retaining the sleeve valve 42 in this initial position until a predetermined pressure differential exists between the fluid pressure in the well bore 6 and the fluid pressure acting on means 22.

In FIG. 4, the means 75 is shown as including the

annular groove 80 with a plurality of circumferentially spaced openings 81 therethrough. One or more shear pins 82 are provided, with one shear pin being provided for each opening 81 and extending therethrough to seat in the annular groove 83 in the sleeve valve 42. In assembly of the tool, the snap ring 71 will be seated in groove 72, and sleeve 42 will then be telescoped into head portion 26. One or more shear pins 82 will then be positioned in the openings 81 and rubber band retainer 84 then placed in groove 80. This holds the shear pins in position while head portions 25 and 26 are being connected together.

The shear pins 82 will be formed of a material of a known shear strength. The area of the sleeve valve 42 exposed to the expanding or inflating fluid within the expandable means 22 is known, and this enables the amount of inflating fluid to be exerted on the expandable means to be controlled in that the valve 42 will move only when the pressure exerted in expandable means 22 thereon exceeds the shear strength of the shear pins 82 and the pressure of the well bore acting on the end 42' of sleeve 42 and tending to hold it in its position shown in FIG. 2 of the drawings. When the pressure within the means 22 exceeds the shear strength of the shear pins 82, the pins will shear and the valve 42 will move longitudinally of the head 20 and seal off further communication between the tubular member 10 and the expandable means 22 so as to lock the inflating fluid within the expandable means and prevent passage of further fluid thereinto.

While it is believed that the operation of the present invention is apparent from the foregoing description, to further amplify and describe, it will be assumed that the tool of the present invention is to be operated in a manner similar to that described in my copending application above referred to. The present tool will be assembled at the earth's surface in which event the valve 42 will be inserted in the portion 26 of the head 20 and shear pins 82 then inserted through their respective openings 81 of groove 80 and retaining band 84 placed in the groove 80 to abut the outer ends of the shear pins 82. Since the shear strength of the material of the shear pins is known, the number of shear pins may be varied, thus determining the amount of pressure differential required to effect movement of the annular valve 42.

Thus, if it is desired that the valve 42 close when the pressure differential between the pressure of the well fluid and the fluid pressure in inflating or expanding means 22 reaches, say, for example, 400 pounds, then the required number of shear pins 82 will be positioned between 26 and 42 to attain a total shear strength of 400 pounds per square inch.

The valve member 42 will be retained in the position shown in FIG. 2 of the drawings as the tool is lowered into the well bore and until the pressure differential of 400 pounds has been exceeded by the inflating fluid. When this occurs, the shear pin, or shear pins, as the case may be, will shear, and the valve is free to move longitudinally of the chamber 41. Movement of the sleeve valve 42 positions spaced seals 44 and 45 so as to span the openings or port means 60 in the tubular member 10. This seals off communication between the tubular member 10 and the expandable means 22 and locks the expanding fluid within the expandable means 22 and prevents further fluid flow to the expandable means 22.

Also, when valve 42 moves to the position shown in FIG. 5, the seal means 46 and 47 span the opening 64 in the sleeve 42 so that pressure in the well bore 6 is sealed off from passing through the port 64.

When it is desired to unseat or release the expandable means 22 from the well bore 6, the tubular member 10 may be rotated to the right so as to unthread the tubular member 10 from the expanded expandable means.

22 by disengagement at the right-hand releasing connection formed by the threads 32. When this occurs, the tubular member 10 may be moved longitudinally relative to expandable means 22 as shown in FIG. 6 so that the longitudinally extending leak grooves or leak passage means 16 span the lower packer head 21 as shown in FIG. 7 and thereby communicate the interior of the expandable means 22 with the well bore 6 so as to discharge the expanding fluid from the expandable means 22.

Thereupon, the well tool 9 may be removed from the well bore.

The fluid supplied to expand means 22 may be conducted from the earth's surface through support means 8 and tubular member 10, or it may be contained within a reservoir on the tool 9.

Broadly, the present invention relates to a well tool, and more particularly to a well tool including a valve arrangement for controlling the inflating fluid pressure or expanding fluid pressure exerted on an expandable member mounted on the well tool by limiting the pressure differential between the well bore and expandable means and by locking the expanding fluid in the expandable means after actuation.

What is claimed is:

1. A well tool adapted to be lowered in a well on a string of pipe comprising, a tubular member for connecting to the well pipe, expandable means supported on said member to be expanded in the well, there being an opening in the string of well pipe and in said member whereby fluid may be conducted to expand said expandable means, movable sleeve valve means surrounding said member and normally open for communicating fluid through said opening to said expandable means, shear means to hold said valve in normally open position, said shear means shearing when the expanding fluid pressure reaches a predetermined amount whereby said valve means moves to close off communication to said expandable means and lock the expanding fluid therein.

2. The invention recited in claim 1 including releasable means connecting said tubular member and expandable means whereby said tubular member and expandable means may be disconnected from each other for relative movement therebetween.

3. The invention recited in claim 2 including leak passage means on said tubular member which, upon relative movement between said tubular member and said expandable means, communicates said expandable means with the well to discharge the expanding liquid from said means.

4. A well tool adapted to be lowered in a well comprising, a tubular member, expandable means supported on said member to be expanded in the well, there being an opening in said member communicating with said expandable means whereby fluid may be conducted to expand said expandable means, and movable sleeve valve means surrounding said member and normally open for communicating fluid through said opening to said expandable means, shear means to hold said valve in normally open position, said shear means shearing when the expanding fluid pressure reaches a predetermined amount whereby said valve means moves to close off communication to said expandable means and lock the expanding fluid therein.

5. The invention recited in claim 4 including releas-

able means connecting said tubular member and expandable means whereby said tubular member and expandable means may be disconnected from each other for relative movement therebetween.

6. The invention recited in claim 5 including leak passage means on said tubular member which, upon relative movement between said tubular member and said expandable means, communicates said expandable means with the well to discharge the expanding liquid from said means.

7. An inflatable packer including a pair of spaced heads, an expandable means secured to said heads and extending therebetween, a tubular member for supporting said heads and means in position on a well string, there being port means in said tubular member whereby fluid may be conducted to said expandable means to expand said expandable means, an annular movable sleeve valve means in one of said heads surrounding said tubular member, seal means between said valve and said tubular member and between said valve and said head, there being port means in said head for communicating pressure in the well to act on said sleeve valve means, shear means connecting said sleeve valve means in said head in normally open position, said valve means being exposed to the expanding fluid in said expandable means whereby said shear means may be sheared when the pressure differential between the expanding fluid and the well fluid acting on said sleeve valve reaches a predetermined amount to thereby shift said valve means to close off communication between said port means in said tubular member and said expandable means and lock the expanding fluid in said expandable means.

8. The invention recited in claim 7 including releasable means connecting said tubular member and expandable means whereby said tubular member and expandable means may be disconnected from each other for relative movement therebetween.

9. The invention recited in claim 8 including leak passage means on said tubular member which, upon relative movement between said tubular member and said expandable means, communicates said expandable means with the well to discharge the expanding liquid from said means.

10. The invention recited in claim 7 wherein said shear means includes shear pins of predetermined shear strength positioned in said head and engaged in a corresponding recess in said sleeve valve.

11. The invention recited in claim 10 wherein the pressure differential between the well fluid and expanding fluid at which said valve becomes operative to lock the expanding fluid in said means may be varied by varying the number of said shear pins to increase and decrease the differential as desired.
